GARMENT PRESSER AND STRETCHER

Percival Frederick Read, Slough, England

Application December 11, 1946, Serial No. 715,372
In Great Britain December 14, 1945

8 Claims. (Cl. 223—61)

1

This invention relates to presses or stretchers for trousers or other garments or articles and has for its object to provide a press or stretcher which may be erected in a vertical position or separated into separate parts for convenience of transport, and which is so constructed as to ensure satisfactory pressing and stretching, whilst reducing the stretching action on a garment or the like when the press is in the closed pressing position.

According to the present invention a press or stretcher for the purpose described is provided with a detachable foot piece which when engaged with the lower end of the press or stretcher holds the latter in a vertical position.

A hinge spring is preferably provided for creating pressure at the lower end of two clamping members.

At the bottom of the press or stretcher, at the bottom of a vertical member or middle board a cuff board is preferably so hinged by a spring that when the press is opened the cuff board is inclined automatically away from a front board to provide space for the turn-ups of trousers. The press or stretcher is preferably provided at its lower end with a pair of spaced angle irons which serve to support the press on the foot piece, a hinge for the front board, and springs for controlling the movement of the cuff board.

At the upper end of the press a stretching board is preferably so mounted that pressure is at its maximum when the stretching board first contacts with a garment or other article and decreases as the press closes.

The stretching board may be maintained at its correct angle for contact with a garment or the like by mounting it on a curved spring rod fitting into a groove.

Rollers over which operating cam levers engage are preferably held in position on a supporting rod by a spring ring which engages with annular grooves in a supporting rod and in the ring.

The upper end of the press may be provided with rails for supporting under or other garments.

The invention will now be described with reference to the accompanying drawings, wherein:

Fig. 1 is a rear elevation of a trouser press.

Fig. 2 is a front elevation of the trouser press shown in Fig. 1.

Fig. 3 is a vertical section on the line III—III of Fig. 1.

Fig. 4 is a view similar to Fig. 3 but with the

press in the open position for receiving a garment.

Fig. 5 is an underside view of Fig. 1.

Figs. 6, 7 and 8 show respectively a longitudinal section of a spindle, and a longitudinal section of the roller mounted on the spindle.

Fig. 9 shows a modified construction of the upper end of the press shown in Fig. 1.

Fig. 10 is a sectional view on line X—X looking at the left hand end of Fig. 9.

Figs. 11 and 12 show views similar to Figs. 1 and 4 of modified form of construction of the lower end of a trouser press.

The same parts in the various figures have the same references.

As shown in the Figs. 1 to 5 a press or stretcher is provided with two clamping boards or members 1, 2. The member 2 has secured to its lower rear end two spaced angle irons 3, 4. The angle irons 3, 4 project from the lower end of the member 2 and the lower ends of their flanges 5, 6 are engaged by metal rods 23, 24 secured to the member or clamping board 2 and of which the outer ends engage with grooves 7, 8 in the inner faces 9, 10 of a pair of feet 11, 12 which are braced together by two rods 13, 14, extending parallel to the member 2. Near the lower end of each rearwardly directed flange 15, 16 of each angle iron 3, 4 is provided a recess 17, 18, whilst each adjacent foot 11, 12 is provided with a recess 19, 20 opposite the recess 17, 18. The free lower ends of the rearward flanges 15, 16 are each provided with a notch 21, 22. By engaging one end of the metal, preferably iron or steel, rod 23, with the recess 17 in one rearward flange 15 and the recess 19 in the adjacent foot 11 and the other end with the notch 22 in the other rearward flange 16 and engaging the second rod 24 in the same manner with the recess 18 in the other rearward flange 16 and the recess 20 of the adjacent foot 12 and with the notch 21 of the rearward flange 15, the clamping board 2 is secured in an upright position to the feet 11, 12.

By disengaging the rods 21, 22 the clamping board 2 can be detached from the feet 11, 12.

The second clamping board or member 1 is hinged at its lower end 25 to the angle irons 3, 4 through the medium of a batten 26 or fillet secured to the lower end thereof. The batten or fillet 26 is adapted to determine the distance to which a garment is to be lowered along the second clamping board 1.

To the batten or fillet 26 is secured at 27, 28 a spring rod 29 which bears against the lower

end of a pair of springs 30, 31 secured to a cuff board 32 and by which it is hinged to the clamping board 2 and which normally urge the cuff board 32 towards the clamping board 1. By means of this arrangement, when the clamping board 1 is moved forwardly into the position shown in Fig. 4, that is to say, into the open position of the press, the cuff board 32 is inclined automatically relatively to the clamping board 2 to provide space for the turn-ups of trousers and recedes when the press is closed.

This arrangement also serves to limit the opening movement of the clamping board 1.

Near the upper end of the clamping board 2 and extending longitudinally near the sides thereof are provided curved spring metal rods 33, 34 transversely across which extends a curved rod 35 at the ends of which are provided cam shaped operating levers 36, 37 which extend forwardly on each side of the press. The cam portions of the operating levers 36, 37 co-operate with rollers of which one is shown at 38 projecting from opposite sides of the front clamping board 1. By this arrangement the front clamping board 1 presses the garment resiliently against the rear clamping board 2.

Each roller 38 is mounted on a spindle 39 through the medium of a spring ring 40 which engages with registering annular grooves 41, 42 in the spindle 39 and roller 38.

In an alternative arrangement shown in Figs. 6, 7, 8, a roller 43 is provided with an undercut recess 44 at the end of its bore 45, whilst a spindle 46 has a conical recess 47 drilled into its end. When the roller 43 is driven on to the spindle 46 the drilled end 47 of the latter is splayed outwardly into the recess 44, whereby the roller 43 is effectively secured to the spindle 46.

Above the rear clamping board 2 is located a stretching board 48 to the back of which is secured a housing 49 in which is mounted a curved spring rod 50 which normally presses the stretching board 48 forwardly. At the ends of the spring rod 50 are provided downwardly extending limbs 51, 52 engaging the ends 53, 54 of a curved spring rod 55 secured at 60, 61 to the back of the rear clamping board 2. The arrangement is preferably such that the stretching board 48 during the closing movement of the front clamping board 1 first serves to stretch the garment and as the front clamping board 1 approaches the clamping position the stretching board 48 moves downwardly and rearwardly so as to reduce the stretching action on the garment.

Rollers 56, 57 may be mounted on the curved spring rod 55 at the ends at which it acts on the limbs 51, 52.

As shown in Figs. 9 and 10 the stretching board 48 may have its curved spring rod 50' hingedly connected to the rear face of the rear clamping board 2' by cranked limbs 51', 52', the free ends of the limbs 51', 52' being hinged to the rear face of the rear clamping board 2' at 61, 62 or in the ends of the springs which act on the connecting rod of the operating levers. The limbs 51', 52' are acted upon by rollers 61' and 61'' at the ends of a curved spring rod 63 mounted at 64, 65 on the rear face of the rear clamping board 2'.

The cuff board may also be mounted in the manner shown in Figs. 11 and 12. The batten or fillet 26' at the bottom of the front clamping board 1' is hinged at 66, 67 on a spring rod 68 engaging at its opposite ends in the angle irons 3', 4'. In the angle irons 3', 4' are mounted one

above the other two further spring rods 69, 70 which are substantially parallel to and above the hinge rod 68 of the front clamping board 1'. On the upper spring 70 are fitted two blocks 71, 72 or metal pressings which bear against the rear face of the rear clamping board 2' at their upper end and have the cuff board 32' secured thereto.

The lower ends of the blocks 71, 72 engage with the ends of the curved spring rod 68 mounted longitudinally on the batten 26'.

The blocks 71, 72 are located behind the spring rods 68, 69, 70 so that as the front clamping board 1' is closed the cuff board 32' is caused to assume an inclined position as shown in Fig. 12, 15 for the purpose hereinbefore described.

The rear clamping board 2 (Fig. 1) is extended upwardly beyond the stretching board 48 by two upstanding side members 73, 74 at each side thereof to which is secured a transverse member 20 75 in which are slidably mounted hangers 76, 77 for other garments, which can be extended laterally of the press.

The angle irons 3, 4 serve to support the press on the feet 11, 12, the front clamping board 1 and cuff board 25 being hingedly mounted thereon, whilst the spring rods 23, 24, 29 for these parts are mounted thereon.

The spring rods 23, 24, 29 may be replaced by blade springs mounted in suitably shaped boxes.

30 What I claim as my invention and desire to secure by Letters Patent is:

1. In a press and stretcher for the purpose described the combination comprising two angle irons secured to the lower end of the press and stretcher in spaced relation, each of said angle irons having a notch in the lower end thereof, a footpiece, two feet secured one to each end of said footpiece, each of said feet having a recess therein and a notch in the lower end thereof,

35 and two spring metal rods, one of said rods engaging at one end with the recess in one of said feet, then engaging with the notch in the adjacent angle iron and the other end of the said rod engaging with the notch in the lower end of the other angle iron, the other of said rods engaging at one end with the recess in the other of said feet, then engaging with the notch in the adjacent angle iron and the other end of said last mentioned rod engaging with the notch at the lower end of the first angle iron.

40 2. In a press and stretcher according to claim 1, the provision of two clamping members, one of said clamping members being hingedly mounted at its lower ends to said angle irons, the other of said clamping members being secured to said angle irons, a cuff board below the lower end of said clamping member secured to said angle irons, springs connecting said cuff board to said last mentioned clamping member, and a spring member acting on said cuff board, the arrangement being such that when the first mentioned clamping member is turned on its hinge the cuff board is inclined automatically away from the first mentioned clamping member to provide space for turn-ups of trousers.

45 3. In a press and stretcher according to claim 1, the provision of two clamping members, one of said clamping members being hingedly mounted at its lower ends to said angle irons, the other of said clamping members being secured to said angle irons, a cuff board below the lower end of said clamping member secured to said angle irons, springs connecting said cuff board to said last mentioned clamping member, and a spring member acting on said cuff board,

the arrangement being such that when the first mentioned clamping member is turned on its hinge the cuff board is inclined automatically away from the first mentioned clamping member to provide space for turn-ups of trousers, a stretching board at the upper end of said second clamping member, and spring mechanism on said second clamping member acting on said stretching board, said stretching board being adapted to apply maximum pressure on a garment when the first mentioned clamping member contacts said garment, said pressure decreasing as the first clamping member approaches the second clamping member.

4. In a press and stretcher according to claim 1, the provision of two clamping members, one of said clamping members being hingedly mounted at its lower ends to said angle irons, the other of said clamping members being secured to said angle irons, a cuff board below the lower end of said clamping member secured to said angle irons, springs connecting said cuff board to said last mentioned clamping member, and a spring member acting on said cuff board, the arrangement being such that when the first mentioned clamping member is turned on its hinge the cuff board is inclined automatically away from the first mentioned clamping member to provide space for turn-ups of trousers, a stretching board at the upper end of said second clamping member, and spring mechanism on said second clamping member acting on said stretching board, said stretching board, during the first portion of the movement of the first clamping member towards the second clamping board, moving upwardly relatively to the second clamping member, whereupon said stretching board moves downwardly relatively to said second clamping member.

5. In a press and stretcher according to claim 1, the provision of two clamping members, one of said clamping members being hingedly mounted at its lower ends to said angle irons, the other of said clamping members being secured to said angle irons, a cuff board below the lower end of said clamping member secured to said angle irons, springs connecting said cuff board to said last mentioned clamping member, and a spring member acting on said cuff board, the arrangement being such that when the first mentioned clamping member is turned on its hinge the cuff board is inclined automatically away from the first mentioned clamping member to provide space for turn-ups of trousers, a stretching board at the upper end of said second clamping member, links connecting said stretching board to said clamping member and a curved spring secured to said second clamping member, said curved spring acting on said links.

6. In a press and stretcher according to claim 1, the provision of two clamping members, one of said clamping members being hingedly mounted at its lower ends to said angle irons, the other of said clamping members being secured to said angle irons, a cuff board below the lower end of said clamping member secured to said angle irons, springs connecting said cuff board to said last mentioned clamping member, and a spring member acting on said cuff board, the arrangement being such that when the first mentioned clamping member is turned on its hinge the cuff board is inclined automatically away from the first mentioned clamping member to provide space for turn-ups of trousers, two spindles secured one to each side of said

first clamping member, each of said spindles having an annular groove therein, two rollers mounted one on each of said spindles, each roller having a recess therein, each recess having an annular groove therein, two spring rings, said spring rings engaging respectively the annular grooves in the spindles and the annular grooves in said rollers, whereby said rollers are secured to said spindles, a pair of spring rods secured to the back of said second clamping member, a pair of cam levers engaging said rollers, and a curved rod connecting said cam levers and co-operating with said spring rods.

7. In a press and stretcher according to claim 15, the provision of two clamping members, one of said clamping members being hingedly mounted at its lower ends to said angle irons, the other of said clamping members being secured to said angle irons, a cuff board below the lower end of said clamping member secured to said angle irons, springs connecting said cuff board to said last mentioned clamping member, and a spring member acting on said cuff board, the arrangement being such that when the first mentioned clamping member is turned on its hinge the cuff board is inclined automatically away from the first mentioned clamping member to provide space for turn-ups of trousers, two spindles secured one to each side of said first clamping member, each spindle being provided with a tapered recess in its end, two rollers mounted one on each spindle, each of said rollers having a bore therein, the inner end of each of said bores being undercut, said rollers being driven on the recessed ends of said spindle, whereby the ends of the spindles are splayed outwardly into the undercut ends of the bores so as to secure said rollers to said spindles, a pair of spring rods secured to the back of said second clamping member, a pair of cam levers engaging said rollers, and a curved rod connecting said cam levers and co-operating with said spring rods.

8. In a press and stretcher according to claim 45, the provision of two clamping members, one of said clamping members being hingedly mounted at its lower ends to said angle irons, the other of said clamping members being secured to said angle irons, a cuff board below the lower end of said clamping member secured to said angle irons, springs connecting said cuff board to said last mentioned clamping member, and a spring member acting on said cuff board, the arrangement being such that when the first mentioned clamping member is turned on its hinge the cuff board is inclined automatically away from the first mentioned clamping member to provide space for turn-ups of trousers, upstanding side members at each side of said second clamping member, a transverse member secured to the upper ends of said upstanding side members, and hangers slidably mounted in said transverse member.
